ILLUMINATED GUIDE LINE

John H. Greene, Little Rock, Ark.

Application July 9, 1937, Serial No. 152,862

4 Claims. (Cl. 177—329)

The present invention has reference to traffic lines used as dividing lines for designating traffic lanes of highways.

An important object of the invention is to provide a traffic line which will be visible in the daylight, and one which may be illuminated so that the traffic line will be clearly visible at night, clearly indicating the traffic lanes, thereby lessening the dangers of night driving.

10 A further object of the invention is to provide a traffic line of this character which will permit light rays to pass therethrough, but at the same time will be exceptionally strong and durable, and one which will not be rendered inoperative under 15 heavy traffic.

A still further object of the invention is to provide a device of this character including a housing so constructed that the material of which the road surface is constructed, will be interlocked with the housing to insure against the 20 road surface shrinking away from the housing.

With the foregoing and other objects in view, which will appear as the description proceeds, the invention resides in the combination and 25 arrangement of parts and in the details of construction hereinafter described and claimed, it being understood that changes in the precise embodiment of the invention herein described, may be made within the scope of what is claimed, 30 without departing from the spirit of the invention.

Referring to the drawing:

Figure 1 is a perspective view illustrating a highway equipped with a traffic line constructed 35 in accordance with the invention.

Figure 2 is a transverse fragmental sectional view through a highway equipped with the traffic line.

Referring to the drawing in detail, the traffic 40 line or traffic lane dividing member embodies a pair of channel bars indicated by the reference character 5, the channel bars having their open sides disposed outwardly, as clearly shown by Figure 2 of the drawing.

45 The open sides of these channel bars provide spaces for the reception of the plastic material of which the road surface is formed, thereby anchoring the plastic material of the road surface, to the channel bars.

50 A base plate indicated by the reference character 6, extends throughout the entire length of the roadway, the lower flanges 7 of the channel bars, being secured to the base plate, in any suitable and well known manner.

55 Disposed between the channel bars 5, and

resting on the base plate 6, is a channel bar indicated by the reference character 8, the channel bar 8 having its open side disposed downwardly, the free edges of the channel bar resting directly on the base plate 6. This channel bar 8, provides 5 a housing for the cable 9, through which the electric wires extend, the electric wires being connected with a suitable source of electricity supply, to supply electric current for the neon tube, to be hereinafter more fully described. 10

The neon tube is indicated by the reference character 10, and is disposed in spaced relation with the surface of the member 11, constructed of transparent material such as pontalite or Bakelite, or with tempered glass blocks, in which 15 the neon tube is supported.

This transparent member 11, is of a width to closely fit against the adjacent surfaces of the channel bars 5, the thickness of the transparent member being equal to the distance between the 20 upper edge of the channel bar 8, and the road surface, providing a smooth and regular surface with the upper flanges of the channel bars 5.

It will of course be understood that the channel bar 8 is provided with openings through which 25 the wires, that supply electric energy to the neon within the tube 10, extend, suitable means being provided to insure a close fit between the wires and channel bar 8, so that moisture will be excluded from the space provided by the channel 30 bar 8.

From the foregoing it will be seen that the upper flanges of the channel bars 5, together with the upper surface of the transparent member 11, provides a traffic line which is clearly 35 visible in the daylight, and that when the electric current is supplied to the neon within the tube 10, the transparent member 11 will be illuminated, providing a red line throughout the entire length of the road surface, dividing the 40 road surface into traffic lanes, clearly visible in the dark. In connection with the illuminated traffic line, it might be stated that it has been found in practice that the traffic line when illuminated, will be clearly visible against the light rays of strong automobile headlights, fog or rain, thereby greatly reducing the dangers of night 45 driving.

Having thus described the invention, what is 50 claimed is:

1. A highway traffic line comprising parallel spaced channel bars having their open sides disposed outwardly, providing spaces to receive material of which the highway is constructed, an- 55

choring the channel members in the road surface, a base plate on which the channel bars are mounted, a channel bar disposed between the first mentioned channel bars and having its open sides disposed downwardly, a glass block disposed between the parallel channel bars and resting on the last mentioned channel bar, the upper surface of the glass block being flush with the upper edges of the spaced channel bars, electric lighting means within the glass block and electric wires housed in the last mentioned channel bar for directing electric energy to the electric lighting means within the glass block.

2. A highway traffic line comprising parallel spaced bars adapted to be embedded in a highway surface, a base plate on which the bars are mounted, means for dividing the space between the bars into upper and lower compartments, a glass block disposed within the upper compartment, the upper edge of the glass block being flush with the upper edges of the bars, electric lighting means within the glass block, and disposed longitudinally thereof, and electric wires housed in the lower compartment for directing

electric energy to the electric lighting means in the glass block.

3. A highway traffic line comprising parallel spaced bars disposed centrally of the highway and arranged longitudinally thereof, means within the space dividing the space into upper and lower compartment, said means including a horizontal partition, a glass block resting on the horizontal partition and extending longitudinally of the highway, electric means in the glass block for illuminating the glass block, and electric wires extending through the lower compartment for directing electric energy to the electric means.

4. A highway traffic line comprising parallel spaced bars disposed centrally of the highway and arranged longitudinally thereof, means within the space dividing the space into upper and lower compartments, said means including a horizontal partition, a transparent block resting on the horizontal partition and extending longitudinally of the highway, and lighting means between the spaced bars for illuminating the block.

JOHN H. GREENE.
